UNITED STATES PATENT OFFICE.

INGRAM LESLIE, OF JOHN, KENTUCKY.

HARROW.

1,254,817.

Specification of Letters Patent. Patented Jan. 29, 1918.

Application filed May 7, 1917. Serial No. 166,979.

To all whom it may concern:

Be it known that I, INGRAM LESLIE, citizen of the United States, residing at John, in the county of Pike and State of Kentucky, have invented certain new and useful Improvements in Harrows, of which the following is a specification, reference being had to the accompanying drawings.

This invention relates to certain improvements in harrows, and has relation more particularly to a device of this general character wherein rotary disks or blades are employed; and it is an object of the invention to provide a device of this general character having novel and improved means whereby the soil may be readily and effectively treated as the device passes thereover.

It is also an object of the invention to provide a novel and improved means of this general character including a harrow section mounted for movement in a vertical direction, together with means for imparting movement to said section in one direction for rendering the same inoperative, as the occasions of practice may require.

It is also an object of the invention to provide a novel and improved device of this character wherein the harrow section is yieldably held in operative engagement with the ground so that said section may have upward movement in the event the same is brought into engagement with an undue obstruction, such as a stone or stump, to compensate for such obstruction.

Furthermore it is an object of the invention to provide a device of this general character which is of a wheel-supported type, and wherein novel and improved means are employed under control of a harrow section for working the ground rearwardly of the device and rearwardly of the supporting wheels.

The invention has for a still further object to provide a wheel-supported device of this general character wherein novel and improved means are employed for controlling the direction of travel of the device independently of the draft animals, and which serves to render the device capable of efficient use when working on a hillside.

The invention consists in the details of construction and in the combination and arrangement of the several parts of my improved harrow whereby certain important advantages are attained and the device is rendered simpler, less expensive and other-

wise more convenient and advantageous for use, all as will be hereinafter more fully set forth.

The novel features of the invention will 60 hereinafter be definitely claimed.

In order that my invention may be the better understood, I will now proceed to describe the same with reference to the accompanying drawings; wherein— 65

Fig. 1 is a view in side elevation of a harrow constructed in accordance with an embodiment of my invention;

Fig. 2 is a view in top plan of the device as herein embodied, with a portion broken 70 away;

Fig. 3 is a view partly in front elevation and partly in section, with portions omitted, of the device herein disclosed;

Fig. 4 is a fragmentary view partly in 75 top plan and partly in section, illustrating certain features of the invention as herein embodied;

Fig. 5 is a sectional view taken substantially on the line 5—5 of Fig. 1; 80

Fig. 6 is an enlarged fragmentary view, partly in elevation and partly in section, illustrating operative connection of a lifting member with a harrow section;

Fig. 7 is a fragmentary view in perspective, illustrating a modified form of ground-engaging member; and 85

Fig. 8 is a fragmentary view, partly in elevation and partly in section, illustrating a modified mounting relative to the rear 90 ground-engaging member.

As disclosed in the accompanying drawings; 1 denotes an elongated beam disposed transversely of the direction of travel of the device, and which has adjustably engaged with the opposite end portions thereof the depending brackets 2, arranged in pairs. Operatively engaged with each pair of brackets 2 is a swinging frame F, substantially U shape in form and having the free 95 extremities of its side members 3 loosely engaged with an axle 4. Mounted upon the outer end portion of the axle 4 is a supporting wheel 5, of any ordinary or preferred type. Loosely or pivotally engaged with the opposite end portions of the axle 4 are the forwardly directed side members 6 of a harrow section, and rotatably supported by the outer or forward end portions of said side sections 6 is the shaft 7, from which radiate the ground-engaging blades 8, of any ordinary or preferred construction, but 100 105 110

preferably of such a transverse twist as to assure an effective treatment of the soil.

I do not wish to be understood as limiting myself in any way as to the particular mounting of the shaft 7, or the blades 8 co-acting therewith.

Rotatably supported by each of the frames F at a predetermined distance above the co-acting axle 4 is a shaft 9 provided at its outer end portion with a gear 10, in mesh with an internal gear 11, suitably affixed to a supporting wheel 5. Slidably mounted upon the shaft 9 is a sprocket wheel 12, provided with a clutch face 14, adapted to coact with a clutch face 15 carried by the gear 10; whereby it will be perceived that when said faces 14 and 15 are interlocked, the gear 12 will be caused to rotate in unison with and in the same general direction as the shaft 9. The lower portion of the sprocket wheel 12 is operatively engaged with the upper stretch of an endless sprocket chain 16, disposed around a sprocket 17 suitably affixed to the shaft 7 of an adjacent harrow section. The chain 16 is also directed around an idle pulley or wheel 18, rotatably supported by the inwardly and upwardly directed end portion 19 of an arm 20. The arm 20 is suitably affixed, as indicated at 21, to the axle 4, and is disposed rearwardly and upwardly from the axle 4 on a predetermined incline, so that the pulley or wheel 18 may be positioned a predetermined distance rearward of the sprocket 12. It is also to be noted that the pulley or wheel 18 is capable of adjustment longitudinally of the end portion 19 of the arm 20, so that the upper stretch of the chain 16 may be maintained in requisite engagement with the sprocket 12.

Suitably secured to the beam 1 and extending forwardly therefrom is a substantially horizontally disposed frame H, including the intermediate parallel beams 21, and having the forward beam between the intermediate beams 21 offset upwardly, as indicated at 22. The space afforded by the offset portion 22 is closed by the strip 23, as clearly indicated in detail Fig. 5. Disposed through the offset portion 22 and resting upon the strip 23, is a tongue T, the inner end portion of which is pivotally engaged, as at 24, at substantially the longitudinal center of the beam 1. It is to be noted that the portion of the tongue T intersecting the horizontal frame H is of skeleton formation, as indicated at 25, in order to prevent the tongue T from obstructing the view of the plant rows with which my improved device may be employed as a cultivator. Disposed longitudinally of the rear portion of the tongue T, and rotatably supported thereby, is a shaft 26, provided at its rear end portion with a hand wheel 27, whereby the requisite rotation may be imparted to the

shaft 26 by the occupant of the seat S. The opposite or forward end portion of the shaft 26 is provided with a pinion 28, in mesh with a rack 29, disposed longitudinally of the offset portion 22 of the frame S. By this arrangement it will be perceived that the direction of travel may be readily controlled independently of the draft animals hitched to the tongue T, so that the device may be properly aligned with the plant rows or prevented from sliding down when working on a hillside, as the draft can be readily equalized or controlled by swinging the tongue T about its pivotal connection 24. The rear portion of the tongue 26 is also provided with a toothed wheel 30, with which is adapted to coact a dog or pawl 31, pivotally engaged with the rear or pivoted end portion of the tongue T, in order to effectively lock the tongue T into different adjustments about the pivot 24.

Rotatably supported by the forward end portions of the intermediate beams 21 and the frame H is a rock shaft 32, provided at each of its end portions with a depending arm 33. Pivotally engaged with the lower end portions of the arm 33 are rearwardly and downwardly diverging rods 34, having their opposite end portions pivotally engaged, as at 35, with the side members 3 of the frame F. Also affixed to the shaft 32 is a rearwardly directed lever 36, terminating in close proximity to the seat structure S, and which is provided with a latch mechanism 37, coacting with a rack 38, carried by one of the beams 21, whereby it will be perceived that the device may be properly balanced in accordance with the weight of the occupant of the seat S. The seat S is suitably affixed to the free end portion of the rear end portion of the tongue T.

The side members 6 of each of the harrow sections are connected by the transversely disposed bar 40, arranged at a predetermined point in advance of the adjacent supporting wheel 5, and said bar 40 is provided at a predetermined point intermediate its length with an opening 41, through which is loosely directed an arm 42, pivotally engaged with a depending arm 43, carried by a second rock shaft 44, supported by the beams 21 of the frame H. The rod 42 is provided with a head or enlargement 45, herein disclosed as a conventional nut threaded upon the lower end portion of the rod 42, underlying the bar 40 and adapted to contact with said bar to raise the harrow section when upward movement is imparted to the rod 42. The rod 42 is moved upwardly upon requisite rocking movement being imparted to the shaft 44, and, as herein disclosed, said shaft 44 is rocked through the medium of a link 46, pivotally engaged with a rock arm 47, depending from the shaft 44 and operatively

engaged with a lever 48, pivotally engaged with a side member 3 of one of the frames F. The lever 48 is provided with a conventional latch mechanism 49, coacting with a 5 rack 50, also carried by the side member 3 of the frame F, whereby the harrow section may be held in its elevated position.

Encircling the rod 42 is a coil spring 51, interposed between the bar 40 and an enlargement or collar 52, carried by the rod 42, whereby it will be perceived that limited upward movement of the harrow section is afforded independently of the rock shaft 44, and which limited upward movement 15 is of special advantage when the blades 8 come in contact with some undue obstruction, such as a stone or stump. It will be self-evident that as soon as the blades 8 pass over the obstruction the spring 51 will force 20 the harrow section downwardly to return the blades 8 to proper engagement with the soil.

It is also my purpose to render the shaft 7 inoperative upon the elevation of each 25 harrow section, and as herein disclosed this function is accomplished through the medium of the rearwardly and upwardly directed arm 53, pivotally engaged at its lower end with the bar 40 of the harrow section, 30 and the upper extremity of said arm 53 is laterally inclined as at 54, to afford a cam action. The inclined port on 54 is directed through a loop 55, carried by the outer side member 3 of the adjacent frame F. The inclined portion 54 is continued in an outwardly and laterally directed extension 56, terminating in an inwardly and forwardly directed fork 57, operatively engaged in a conventional manner with the hub portion 40 58 of the sprocket wheel 12. It is thought to be self-evident that upon the elevation of a harrow section, the cam portion 54 of the arm 53 will cause the sprocket 12 to move inwardly a distance sufficient to dis- 45 engage the clutch faces 14 and 15.

I also find it of advantage to provide a ground-engaging member adapted to coact with the soil rearwardly of the supporting wheels 5. As herein disclosed I employ a 50 substantially U shape ground-engaging member M, having the free end portions of its side members 59 pivotally engaged with the side members 6 of a harrow section. The intermediate portion 60 of the member M is disposed on a predetermined incline relative to the direction of travel of the machine, so that a more effective action 55 may be had upon the soil. It is also to be noted that the side members 59 are disposed outwardly of the members 6 of a harrow section so that the intermediate portion 60 intersects the line of travel of the adjacent supporting wheel 5. The intermediate portion 60 of the member M is adapted to drag 60 on the surface or just therebeneath, and

serves to pulverize the soil and press it together under the surface, leaving a loose dust mulch on top which prevents evaporation of moisture. It is also to be understood that the ground-engaging member M 70 is provided in connection with each of the harrow sections.

It is also desired that each of the members M be elevated out of contact with the soil upon elevation of its coacting harrow 75 section. As herein embodied this is accomplished through the medium of a rock arm 61 supported by the side members 6 of a harrow section, and which is provided with the rearwardly directed rock arms 62, 80 terminating in eyes 63, through which the side members 59 of the member M are loosely directed. The shaft 61 is also provided with an upstanding rock arm 64, with which is pivotally engaged a rod 65, which 85 is also pivotally engaged as at 66, with the forward end portion of one of the intermediate beams 21 of the frame H. It will be at once self-evident that as the harrow section is raised, the rock arm 64 will be forced 90 downwardly, resulting in an elevation of the rock arm 62, and a corresponding elevation of the member M.

If preferred, the intermediate portion of the rear ground-engaging member may be 95 in the nature of a cutting blade, as indicated at 67 in Fig. 7 of the accompanying drawings; and when the blade 67 is employed, I find it of advantage to provide each end thereof with a forwardly directed wing 68, 100 pivotally engaged as at 69 with a side member 59a. I also find it of advantage to provide the side member 59a and the adjacent wing 68 with a coacting means 70, whereby the blade 67 may be disposed on different 105 pitches, as the necessities of practice may dictate.

I also find it desirable to provide the dog or pawl 31 with a latch mechanism 71 adapted to coact with a rack 72 carried by the 110 rear end portion of the tongue T, whereby the dog or pawl 31 may be positively locked in mesh with the toothed wheel 30, or out of engagement therewith.

In Fig. 8 I illustrate a modified mounting 115 for the upper end portion of the rod 65. As herein disclosed the upper end portion of the rod 65 is pivotally engaged at 73 with a lower end portion of an elongated member or bar 74 loosely disposed through the 120 adjacent intermediate beam 21a. The member or bar 74 is constantly urged upwardly through the medium of an expansible member 75, herein disclosed as a coil spring encircling the member or bar 74, and interposed between the beam 21a and a stop or head 76 carried by the upper end portion of the member or bar 74. As herein disclosed the stop or head 76 comprises a conventional nut or bur threaded upon the 125

upper end portion of said member or bar 74. The opposite end portion of the member or bar 74 is provided with a stop or head 77 adapted to engage the under face 5 of the beam 21^a, whereby the upward movement of the member or bar 74 under the influence of the expansible member 75 is limited. By the use of the structure particularly illustrated in Fig. 8 it will be at 10 once self-evident that in the event the rear ground-engaging member, such as M, should contact with an undue obstruction, such as rocks and stumps, the ground-engaging portion of said member will readily ride there- 15 over. It will also be self-evident that the expansible member 75 serves to maintain the rear ground-engaging member in proper contact with the soil.

From the foregoing description, it is 20 thought to be obvious that a harrow constructed in accordance with my invention is of an extremely simple and comparatively inexpensive nature and is particularly well adapted for use by reason of the convenience 25 and facility with which it may be assembled, and it will also be obvious that my invention is susceptible of some change and modification without material departure from the principles and spirit thereof, and for this 30 reason I do not wish to be understood as limiting myself to the precise arrangement and formation of the several parts herein shown in carrying out my invention in practice, except as hereinafter claimed.

35 I claim:

1. A harrow including a movable section, a ground engaging member carried by the section, means for imparting movement to the section in one direction, a second 40 ground engaging member operatively engaged with the harrow section, and co-acting means carried by the harrow section and the second ground engaging member for throwing the second ground engaging mem- 45 ber into an inoperative position upon move- ment of the harrow section in one direction.
2. A harrow as specified in claim 1 where- in the harrow section and the second ground

engaging member are mounted to swing in a vertical path.

3. A harrow including a swinging section, a ground engaging member carried by the section, means for imparting swinging movement to the section in one direction, a second ground engaging member pivotally 55 engaged with the harrow section, a rock arm carried by the harrow section, the outer end portion of the arm having sliding engagement with the second ground engaging member, and means co-acting with the rock 60 arm for moving the same upwardly upon the movement of the harrow section in one direction.

4. A harrow as specified in claim 3 where- in the means for moving the rock arm com- 65 prises a shaft mounted upon the harrow section and with which the rock arm is en- gaged, an upstanding rock arm carried by the shaft and a rod pivotally engaged with the upstanding rock arm and with the har- 70 row at a point above the harrow section.

5. A harrow including a frame, a shaft rotatably supported by the frame, clutch controlled means for rotating the shaft and including a sliding member, a harrow sec- 75 tion carried by the frame and mounted for swinging movement, means for imparting movement to the harrow section in one direction, an arm pivotally engaged with the harrow section, and having its free end por- 80 tion operatively engaged with the sliding member of the clutch, an intermediate portion of the arm being inclined, and a guide car- ried by the frame through which the inclined portion of the arm is directed, said inclined 85 portion of the arm and guide serving to render the clutch controlled means for driv- ing the shaft inoperative upon movement of the harrow section in one direction.

In testimony whereof I hereunto affix my 90 signature in the presence of two witnesses.

INGRAM LESLIE.
